WILLIAM RAEURN, OF WATERBURY, CONNECTICUT, ASSIGNOR TO THE MATTATUCK MANUFACTURING COMPANY, OF WATERBURY, CONNECTICUT, A CORPORATION OF CONNECTICUT.

METHOD OF MAKING CHAIR GLIDES.

Application filed February 16, 1925. Serial No. 9,552.

My invention relates to the manufacture of chair glides and has for its object to produce a new and improved method of making the same. An object of my invention is to produce a novel method of making a circular chair glide having securing prongs located at points inside of a circular rim, so as to enter the wood in the chair farther from the edge than they would if extending from the circular rim. Another object of my invention is to provide a new and improved method in which the chair glide will be more accurately formed and in which the work done in the final operation shall be reduced. Another object of my invention is to provide a novel method of making a chair glide having prongs whose bases are located below the plane of the edge or upper plane of the disk and in which the prongs are reinforced by having the rim of the disk engage the rear face of the prongs. Another object of my invention is to provide a novel method whereby in the cupping operation projections upon the cupped portion will be brought behind the prongs and into position to be further acted upon in the succeeding step with a combined bending and swedging action.

Sheet metal chair glides commonly used have the prongs extending from a circular rim so that they are in some cases so near to the periphery of the chair leg to which they are applied as to cause the wood to split. Attempts have been made to avoid the difficulty due to the peripheral prongs and this has been done by indenting the portion of the rim from which the prongs extend, thus sacrificing the circular form of the glide, to the disadvantage of the product in other respects. In glides made by my method the advantages of the inset prongs and the circular form are both preserved.

The following is a description of my improved process embodying my invention, reference being had to the accompanying drawings, in which,

Fig. 1 shows in perspective a chair with glides on the bottoms of the legs thereof;

Fig. 2 is a blank used in making chair glides according to my method;

Figs. 3 and 4 are a plan view and a side elevation of the blank of Fig. 2 after performing the first forming step thereon;

Fig. 5 is a section of Fig. 3 on the line 5—5, Fig. 3;

55

Figs. 6 and 7 are plan and side elevations of the second forming step of my process;

Fig. 8 is a section on the line 8—8, Fig. 6;

Figs. 9 and 10 are plan and side elevations of the completely formed glide, ready to be hardened and polished; and

Fig. 11 is a section of the glide on the line 11—11, Fig. 9.

In carrying out my process I first strike out a sheet-steel blank in the form shown in Fig. 2 having three peripheral arcs 2 with extensions 4 between them. I then subject this blank to a series of forming steps. In the first forming step I subject the blank to the action of suitable dies and with one stroke sever the central portions 6 of the extensions 4 from the lateral portions thereof along the lines 5—5 producing prongs 6 and bending the same upward as is shown in Figs. 4 and 5 and leaving projections 8—8 adjacent to each prong. I then subject the product shown in Fig. 3 to the action of ordinary cupping dies and with a single stroke form it into the shape shown in Figs. 6 and 7. In this cupping action a concavo-convex 80

face is formed and the prongs 6 are brought into a vertical position so as to be parallel to one another, and the projections 8 are brought behind their adjacent prongs, as shown most clearly in Fig. 7. The two projections constituting any pair of projections are at this stage inclined toward one another behind their adjacent prongs at points above the plane of the edge portions between the several pairs of projections. This results from the cupping of the device shown in Figs. 4 and 5 and leaves the projections in a position so that when they are bent down and swaged they are brought in close contact with one another, as shown in Fig. 95

10. The product shown in Figs. 6 and 7 is then subjected to another set of dies one of which has a portion passing outside the parallel prongs 6—6 and engaging the projections 8—8 brings them down by a bending and swedging action into the position shown at 12 in Figs. 9 and 10.

In the resulting product the prongs 6 are inside the rim of the glide, the body of the glide itself being circular, and the projections 12 are behind the prongs so as to en-

gage the same throughout their width and well above their bases and reinforce them so as to enable them to withstand the blows hit in applying the glide to the leg of the 5 chair, as shown at 14, Fig. 1. The distance between the outer surfaces of the prongs and the axis of the glide is thus equal to the distance between the inner surfaces of the rim and also the projections 12 and that axis. 10 10 The bending and swedging action to which the projections 8—8 are subjected brings the metal of two adjacent projections into close contact as shown at 12, Figs. 9 and 10, thereby fully completing the circular rim of 15 the glide and closing the opening, which would otherwise be left by cutting the metal so as to disconnect the prongs 6 from the rim.

Heretofore circular chair glides having prongs removed from complete rims have, 20 so far as I know, only been made by casting, which is a slow and expensive method of manufacture as compared with making them from sheet metal. By my process I am enabled to make from sheet metal a circular chair glide having a complete circular periphery and prongs removed from said periphery and disconnected from the rim, although reenforced thereby. The bases of the prongs are approximately in the plane 25 of the front face 16 of the cupped disk as distinguished from being in the plane of the rim or rear face of the cupped disk, this being necessary in order to secure a sheet metal chair glide of truly circular shape free from 30 peripheral openings.

The metal employed in carrying out my process is sheet steel and after the product shown in Figs. 9 and 10 is obtained, this product is subjected to any suitable hardening 40 process and then polished to make it ready for the market. One of the great advantages of my process is that in cupping the product shown in Figs. 3 and 4 it is by a single stroke brought into the form shown 45 in Figs. 6 and 7 with the projections 8 extending partially behind the prongs 6 and inclined so that by a single blow of comparatively light pressure they can be bent and swedged down into the position shown 50 in Figs. 9 and 10. This automatic positioning of the projections 8 as shown in Figs. 6 and 7 insures the accurate bending and swaging of the prongs in the next succeeding step.

In carrying out my process I preferably 55 in the first forming step leave the prongs 6 at an angle to each other and outwardly inclined to the central portion 18, as shown in Figs. 4 and 5, thus contributing to the ease in placing the partially formed chair 60 glide in the dies for the next succeeding operation. At the end of this step the projections 8—8 are in the plane of the portion 18 which insures the proper action in the succeeding cupping step.

65 As will be evident to those skilled in the

art, my invention permits of various modifications without departing from the spirit thereof or the scope of the appended claims.

What I claim is:

1. In the method of producing chair 70 glides, the improvement which consists in forming a cup-shaped body with a plurality of pairs of projections extending from its rim and a corresponding plurality of prongs having their outer surfaces removed from the axis of said body to substantially the same extent as the inner surfaces of the cup rim and of said projections, each prong being adjacent to the space between the members of one pair of said projections and between said projections and the axis of the cup, and then forcing the metal of said projections downwardly behind said outer surfaces of said prongs. 75

2. In the method of producing chair 80 glides, the improvement which consists in forming a blank having a plurality of outwardly extending portions, then forming upwardly extending prongs from the central parts of each of said portions and leaving 85 projections adjacent to said prongs, then cupping this product so as to bring the axes of said prongs substantially parallel and to bend said projections behind their adjacent prongs, and then forcing said projections 90 downwardly behind said prongs. 95

3. In the method of producing chair 100 glides, the improvement which consists of forming a blank having a plurality of outwardly extending portions, then forming upwardly and outwardly extending prongs from the central portion of each of said portions and leaving projections adjacent to the sides of said prongs and in the plane of the body of said blank, then cupping this product so as to bring the axes of said prongs substantially parallel and to bend said projections 105 behind their adjacent prongs, and then forcing said projections downwardly behind said prongs. 110

4. In the method of producing chair 115 glides, the improvement which consists in forming a blank having a plurality of outwardly extending portions, then forming upwardly extending prongs from the central parts of each of said portions and leaving laterally extending projections adjacent to said prongs, then cupping this product so as to form a concavo-convex face, to bring the axes of said prongs substantially parallel and to bend said projections so that they are inclined toward one another behind their adjacent prongs at points above the plane of the edge portions between the said pairs of projections, and then forcing said projections downwardly behind said prongs. 120 125

In testimony whereof, I have signed my name to this specification this 11th day of February, 1925.

WILLIAM RAEURN.
